Richard Oliver,

ATTORNEY

UNITED STATES PATENT OFFICE.

JAMES W. WHITE, OF BAINBRIDGE, GEORGIA.

MAIL CATCHER AND DELIVERER.

1,289,335.

Specification of Letters Patent. Patented Dec. 31, 1918.

Application filed June 11, 1917. Serial No. 174,077.

To all whom it may concern:

Be it known that I, JAMES W. WHITE, a citizen of the United States, residing at Bainbridge, in the county of Decatur and 5 State of Georgia, have invented certain new and useful Improvements in Mail Catchers and Deliverers, of which the following is a specification.

This invention relates to mail catching 10 and delivering mechanism, the object of which is to provide automatically operated mechanism which will not subject the mail bags to undue thrust.

A further object of the invention is to provide mail bag handling apparatus adapted 15 to effect an automatic transfer of mail or other packages to a moving train from a fixed platform beside the track, which embodies simple and effective mechanism for 20 performing this function, and which has its various parts so constructed and arranged as to minimize the opportunity for wear or breakage, and which performs the transferring operation in such manner as to present 25 the least possible opportunity for breakage of the bag or injury to the contents thereof.

The above and other objects and advantages of this invention will be in part described and in part understood from the following description of the present preferred embodiment, the same being illustrated in the accompanying drawings, in which:

Figure 1 is a side elevation of a mail delivery station constructed in accordance with 35 my invention and a sectional view of a mail car receiving apparatus of my invention, and

Fig. 2 is a detail perspective of the bag holding apparatus and releasing mechanism.

In Fig. 1 of the drawings a portion of a mail car 1 is shown which is equipped with the usual lateral openings in which I have mounted mail receiving apparatus used in carrying out the invention. The apparatus 45 in this instance consists of a rod 2 mounted on the floor of the car but spaced therefrom and having a gate 3 slidably mounted thereon. Wings 4 are pivotally engaged with the opposite ends of the gate and are equipped 50 with links 5 which engage arms 6 in order to retain the gate 3 in an inclined position. It will be noted that the wings 4 are so formed as to lie between the inner face of ends of the gate 3 and the outside of the

car 1, thereby preventing longitudinal dis- 55 placement of the bag while it is gravitating on said gate 3, toward the car.

A delivering platform 8 is arranged beside the track, and is suitably supported by the uprights indicated at 7. This platform 60 is inclined upwardly and outwardly away from the track, and the forward edge of the same is disposed in substantially vertical alignment with the outer upper edge of the receiving apparatus carried by the car. 65

A retaining finger 10 is disposed vertically beneath the platform 8, and protrudes loosely through the latter near the upper end thereof. This retaining finger is held 70 in proper position beneath the platform by the bearing block 13, and when the said finger is at the limit of its upward movement the upper end thereof protruding through the outer face of the platform engages in a suitable opening in the end of a strap 11 75 secured to the mail pouch or bag 12. The lower end of this finger has affixed thereto an arm 9, and this bag retaining mechanism including the finger is held at the limit of its upward or operative position by an arm 80 16 affixed to the upper end of a rotatable shaft 17 suitably supported in the supporting structure for the platform. The lower extremity of the shaft 17 is equipped with an arm 15, the mechanism indicated at 85 16—17—15 constituting the trip mechanism. The finger 10 tends normally to move downwardly under impulse of the spring 14 encircling the said finger and bearing at its upper end against the under surface of the 90 block 13.

In operation, the finger 10 is lifted until the upper end thereof protrudes through the platform 8, whereupon the foot mechanism 95 is moved into such position that the arm 16 thereof will pass beneath and support the arm 9 of the bag retaining mechanism. When the trip mechanism has been so moved, the arm 15 thereof will project forwardly 100 at substantially right angles to the railroad track and will be disposed in the path of travel of the outer end of the receiving apparatus carried by the car. The mail bag is then held by the finger by engaging the looped end of the strap 11 thereof over the upper end of the retaining finger 10. When 105 the train approaches, the forward end of the receiving basket engages the arm 15 causing

the latter to rotate and to move the arm 16 from beneath the forwardly projecting arm 9 of the bag holding apparatus. When the arm 16 has moved from beneath the arm 9, 5 the spring 14 will cause the finger 10 to move downwardly, retracting the upper end of the said finger. This downward movement of the finger causes the looped end of the retaining strap 11 to be disengaged, 10 whereupon the bag 12 will gravitate into the receiving basket carried by the car.

It is obvious from the foregoing that I have provided a mail bag transferring apparatus which is of extremely simple and 15 inexpensive construction and which is wholly automatic in its delivering operation. No attention need be paid to the apparatus after the bag is once positioned properly thereon, and the use of an apparatus such as this obviates the necessity for the mail clerk in the car remaining in the doorway during the transferring operation.

The foregoing description and the drawings have reference to what may be considered the preferred, or approved, form of 25 my invention. It is to be understood that I may make such changes in construction and arrangement and combination of parts, materials, dimensions, et cetera, as may 30 prove expedient and fall within the scope of the appended claims.

I claim:

1. In a mail transferring apparatus, an 35 inclined platform, a finger slidably mounted in said platform and normally protruding therethrough at one end, a trip mechanism for maintaining said finger protruding from said platform, and an arm carried by said tripping mechanism adapted to be engaged

by an approaching car to move said tripping 40 mechanism to releasing position.

2. In a mail transferring apparatus, an inclined platform, a finger slidably mounted in said platform, a tripping mechanism, means on said mechanism for holding said 45 finger with one end protruding through said platform, means tending normally to force said finger into retracted position, and an arm included in said tripping mechanism and adapted to be engaged by a car to move 50 the tripping mechanism to releasing position.

3. In a mail transferring apparatus, a platform, a finger slidably mounted in said platform, an arm at the lower end of said 55 finger, a shaft, an arm on said shaft adapted to move beneath and to support said finger arm, a spring tending to move said finger toward said shaft arm, and a second arm secured to said shaft and extending outwardly 60 therefrom to be engaged by a moving car.

4. In a mail transferring apparatus, in combination, an inclined platform beside the track, a mail receiving apparatus on the car, the outer side of said apparatus being 65 disposed at the same angle as said platform and in the same plane therewith, a holding mechanism on said platform, a trip mechanism, and an arm secured to said trip mechanism and protruding into the path of travel 70 of said receiving apparatus.

In testimony whereof I affix my signature in presence of two witnesses.

JAMES W. WHITE.
